WITNESS:

B. H. Prichard
INVENTOR
BY *Victor J. Evans*
ATTORNEY'S

UNITED STATES PATENT OFFICE.

BENJAMIN H. PRICHARD, OF WASHINGTON, DISTRICT OF COLUMBIA.

GAME.

Application filed June 8, 1922. Serial No. 566,796.

To all whom it may concern:

Be it known that I, BENJAMIN H. PRICHARD, a citizen of the United States, residing at Washington, in the District of Columbia, have invented new and useful Improvements 5 in Games, of which the following is a specification.

This invention relates to games, and comprehends an apparatus which embodies an 10 inclined run-way over which a ball is adapted to be rolled, the ball subsequently entering a depression provided centrally in a substantially disk-like member arranged at one end of the run-way, immediately beneath a 15 pendulum adapted to contact the upper surface of the ball after it has been positioned in the depression, the pendulum cooperating with numbers or other indicia with which the ball is provided to indicate the winner. 20 The nature and advantages of the invention will be better understood when the following detailed description is read in connection with the accompanying drawing, the invention residing in the construction, combination, and arrangement of parts as 25 claimed.

In the drawing forming part of this application, like numerals of reference indicate similar parts in the several views, and 30 wherein:—

Figure 1 is a perspective view of the apparatus.

Figure 2 is a fragmentary sectional view 35 of a portion of the run-way and disk-like member, and showing the position of the ball with relation to the pendulum just prior to the ball entering the depression.

Figure 3 is a view of the ball.

Referring to the drawing in detail, A 40 indicates a run-way, which is angular in formation, open at one end onto a disk-like member 10, which is inclined toward a central depression 11 as clearly illustrated in Figure 2. This disk is surrounded by a wall 12, which 45 prevents the ball from rolling off the disk incident to the playing of the game. The run-way above referred to may vary in configuration without departing from the spirit of the invention, but preferably includes an 50 intermediate portion 13 and parallel end portions 14 and 15 respectively. The portion 15 is comparatively short, inasmuch as it opens into the disk-like member 10 above described, the forward end of this member 55 terminating substantially in the same plane with the forward end of the parallel portion

14. Supported by the wall 12 surrounding the disk-like member 10 is an inverted U-shaped frame 16, and depending from this frame is a pendulum 17 which terminates directly above the central depression 11 of the member 10. 60

The pendulum is spaced from the depression so that when the ball 18 is arranged within the depression, the lower end of the pendulum will rest upon the upper surface of the ball. Arranged in juxtaposition to the run-way and parallel with the intermediate portion 13 thereof is a board 19 containing numbers arranged in consecutive order, and it is of course understood that these numbers can be arranged from one to any desired number. The ball 18 is provided with spaced circles 19, certain circles intersecting other circles so as to provide the ball with a plurality of spaces 20, each of which contains a number corresponding to one of the numbers contained on the board or strip 19. The numbers on the ball are so arranged that when the ball finds its way to the depression 11, one of these numbers will be positioned to be engaged by the adjacent end of the pendulum 17. 70

The apparatus is primarily designed for use in amusement parks or the like, and the manner of using the apparatus can vary. For instance, the players may select one of the numbers on the board 19, laying the coin on the particular number selected, or paddles of well-known construction, bearing numbers corresponding to the numbers on the board 19 may be sold. In either instance, the owner of the apparatus starts the ball from one end of the run-way A, and as this run-way is inclined with respect to the disk-like member 10, the ball continues on its journey until it enters upon the disk-like member 10 as will be readily understood. The member 10 is also dished or inclined toward the center, and the ball eventually finds its way into the depression 11. Just prior to finding its way into this depression, it contacts the pendulum 17, causing the latter to swing from its support, and as the pendulum seeks its point of rest, it contacts a surface of the ball and occupies one of the spaces 20 thereon. The number embodied in this particular space determines the winner. The apparatus is simple in construction, and is designed to afford considerable amusement and pleasure to all those who participate in playing. 105 110

While it is believed that from the foregoing description, the nature and advantages of the invention will be readily apparent, I desire to have it understood that I do not 5 limit myself to what is herein shown and described, and that such changes may be resorted to when desired as fall within the scope of what is claimed.

What I claim is:—

- 10 1. A game apparatus comprising a disk-like member inclined toward the center and having a central depression, a run-way closed at one end and opening at the other and onto said disk-like member, a support, 15 a pendulum suspended from the support and directly above said depression, a ball adapted to be rolled over the run-way and eventually finds its way into said depression, said ball imparting movement to the pendulum just prior to its entrance into the depression, and said ball being provided with indicia cooperating with said pendulum to indicate the winner.
- 20 2. A game apparatus comprising a substantially disk-like member inclined toward the center and having a central depression, a wall surrounding the disk-like member, a support, a pendulum suspended from the support and arranged directly above said depression, a run-way of angular formation and inclined with respect to said disk-like member, said run-way being closed at one end and opening at the other end onto said disk-like member, a ball adapted to gravitate over the run-way onto the disk-like member and into said depression,

said ball imparting movement to the pendulum just prior to entering the depression, and indicia on said ball cooperating with said pendulum to determine the winner. 40

3. A game apparatus comprising a disk-like member inclined toward the center and having a central depression, a wall surrounding said disk-like member, a run-way arranged at an inclination to said disk-like member and opening at one end to said member, a frame supported by the disk-like member, a pendulum suspended from said frame and arranged directly above said depression, a strip containing a plurality of 45 numbers, a ball adapted to gravitate over the run-way onto the disk and into said depression, said ball imparting movement to the pendulum prior to its entrance into the depression, and numbers on said ball corresponding to the numbers on said strip, and 50 cooperating with said pendulum to indicate the winner. 55

4. A game comprising a member inclined toward the center and having a central depression, a support, a pendulum suspended from the support directly above said depression, a ball adapted to be rolled on said member, and eventually find its way into said depression, said ball imparting movement to the pendulum prior to its entrance to the depression, and indicia on said ball cooperating with said pendulum for the purpose specified. 60

In testimony whereof I affix my signature. 70

BENJAMIN H. PRICHARD.
